GAME WALL

Martin Seligson, 404 E. 66th St., New York, N.Y.

Filed May 14, 1963, Ser. No. 74,881

Term of patent 14 years

(Cl. D34—5)

FIG. 1 is a perspective view of one side of a game wall, embodying my new design; and

FIG. 2 is a perspective view of the opposite side thereof.

The dominant features of my design reside in the portions shown in full lines.

I claim:

The ornamental design of a game wall, substantially as shown and described.
